Filed Nov. 19, 1962, Ser. No. 72,535

Term of patent 14 years

(Cl. D58—2)

FIG.1

The characteristic feature of my design resides in the combination on the shoe bag disclosed of a hook supported quilted dividing member having transparent loops or open shoe retaining pockets arranged on each side in a paired relationship, extending substantially the full length and width of the dividing member.

I claim:
The ornamental design for a shoe bag, as shown and described.
